US00D747264S

(12) **United States Design Patent** (10) **Patent No.:** **US D747,264 S**
Kitsugi et al. (45) **Date of Patent:** **** Jan. 12, 2016**

(54) **BATTERY**

(71) Applicant: **Nikon Corporation**, Tokyo (JP)

(72) Inventors: **Yasuo Kitsugi**, Saitama (JP); **Toshiaki Kobayashi**, Fukushima-ken (JP); **Hideaki Asano**, Chiba (JP); **Takasumi Murase**, Chigasaki (JP); **Masuhiro Yamasaki**, Tokyo (JP)

(73) Assignee: **Nikon Corporation**, Tokyo (JP)

(**) Term: **14 Years**

(21) Appl. No.: **29/497,842**

(22) Filed: **Jul. 29, 2014**

(30) **Foreign Application Priority Data**

Jan. 30, 2014 (JP) 2014-001819

(57) **CLAIM**

The ornamental design for a battery, as shown and described.

DESCRIPTION

FIG. 1 is a front, top and right side perspective view of a battery showing our new design;

FIG. 2 is a rear, top and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

1 Claim, 8 Drawing Sheets
